UNITED STATES PATENT OFFICE.

RODERICK J. WHELAN, OF ELYRIA, OHIO.

MACHINE FOR FORMING PROJECTILE SHELLS.

1,218,143.

Specification of Letters Patent. Patented Mar. 6, 1917.

Application filed November 15, 1916. Serial No. 131,540.

To all whom it may concern:

Be it known that I, RODERICK J. WHELAN, a citizen of the United States, residing at Elyria, in the county of Lorain and State 5 of Ohio, have invented new and useful Improvements in Machines for Forming Projectile Shells, of which the following is a specification.

This invention relates to a machine for 10 forming projectile shells in which the nose is forged integral with the body of the shell, the machine comprising, generally a steam or power hammer between the dies of which the shell is fed by a carriage having means 15 for gradually advancing it and means for rotating the shell to present all portions of its nose to the dies and render it uniformly smooth and solid.

In order to obtain the best results, it is 20 important that the machine be so organized that the advancement of the shell as well as its rotation is under the control of one and the same operator, and it is the object of my invention to produce an efficient machine which affords this advantage.

In the accompanying drawings: Figure 1 is a side elevation of the machine, partly in section. Fig. 2 is a sectional elevation, the sectional portion being on line 2—2, Fig. 4. 30 Fig. 3 is a horizontal section on line 3—3, Fig. 2. Fig. 4 is a transverse section on line 4—4, Fig. 1.

Similar characters of reference indicate corresponding parts throughout the several 35 views.

1 indicates the base of a steam or power hammer of any ordinary or well-known construction, upon which is mounted the lower fixed die 2. Coöoperating with this die is the 40 customary upper die or hammer-head 3 carried by the plunger 4 which operates in the usual cylinder 4^a of the hammer. These dies are properly shaped to produce the front or nose portion of the shell 5. The rear end 45 of this shell is tightly clamped in a holder or chuck 6 of any suitable construction carried by a rotary spindle 7 journaled in a carriage 8. This carriage is movable toward and from the dies of the steam hammer and 50 is guided on horizontal ways 9 mounted upon a pair of parallel longitudinal I-beams or equivalent fixed supports 10, these beams preferably resting at their front ends upon the base 1 of the steam hammer and at their 55 rear ends upon a suitable bed or standard 11. Secured centrally to the underside of the

carriage 8 is a rack bar 12 with which meshes a pinion 13 secured to a transverse shaft 14 supported in bearings carried by the I-beams 10. Mounted on one end of this shaft is a 60 large gear wheel 15 which meshes with a pinion 16 secured to a countershaft 17 also supported in said I-beams and provided at that side of the machine at which the operator stands with a hand wheel 18 for turning it to advance or retract the carriage.

The chuck-spindle 7 is preferably rotated by a rotary air or other suitable motor 19 through the medium of any appropriate transmission gearing. In the construction 70 shown in the drawings, this motor is arranged centrally and longitudinally above the chuck-spindle and supported between the upper ends of a pair of standards 20 secured to the carriage 8 on opposite sides of the spindle. The rotary driving shaft 21 of the motor is provided at its rear end with a pinion 22 which meshes with a gear wheel 23 secured to the rear end of the spindle. As the motor is of ordinary construction, it 75 is not illustrated in detail. It contains the customary rotor which is secured to the driving shaft 21 to rotate it and the chuck-spindle geared thereto.

24 indicates a pipe by which compressed air or other pressure fluid is supplied to the motor, the passage of the fluid through this pipe being controlled by a valve 25 of any ordinary construction, having a hand lever 26 for operating it. This lever may be 80 locked in position by a toothed segment 27 secured to the adjacent standard 20, or by any other suitable means. The operating lever of this valve is located at the same side of the machine as the hand wheel 18 for 85 operating the carriage 8 and in close proximity to said wheel, so that the latter and the valve can be conveniently manipulated by one and the same operator in order to obtain the desired coöperation between the 90 advancing and the rotary movements of the shell to properly form its nose. For this purpose, the valve lever is conveniently arranged a short distance above the hand wheel 18, as shown.

Preparatory to placing the shell in the machine, it is heated to a temperature suitable for forging in the customary manner. The carriage 8 is withdrawn to its initial position and the rear end of the shell is 110 clamped in the chuck of the rotary spindle 7. The steam hammer being set in motion,

the carriage is advanced to bring the nose of the shell between the dies. As the forging operation progresses, the shell is gradually fed farther between the dies by turning the hand wheel 18 and simultaneously with this advancing movement the shell is rotated by admitting the pressure fluid to the motor 19. As the shell is fed forward, it is rotated at a gradually increased speed by opening the fluid-supply valve accordingly, this accelerated rotation of the shell being necessary in order to finish the nose smoothly and condense the metal uniformly on all sides.

15 While I have herein shown and described an air motor for producing the rotary motion of the shell, any other suitable motive device, such as an electric motor, may be employed, if desired.

20 I claim as my invention:

1. In a machine of the character described, the combination of a pair of coöperating dies, a carriage movable toward and from said dies, a rotary spindle journaled in 25 said carriage and carrying a shell-holder, means for feeding the carriage toward the dies, means for imparting rotary motion to said spindle, and independent controlling devices for said carriage-feeding means and 30 said spindle-rotating means, both arranged in sufficiently close proximity to each other to be manipulated by one and the same operator.

2. In a machine of the character described, the combination of a pair of coöperating dies, a carriage movable toward and from said dies, a rotary spindle journaled in said carriage and carrying a shell-holder, means for feeding the carriage toward the 40 dies, a rotary motor, gearing for transmitting rotary motion from said motor to said spindle, and separate controlling devices for said carriage-feeding means and said motor located in close proximity to each other.

45 3. In a machine of the character described, the combination of a pair of coöperating dies, a carriage movable toward and

from said dies, a rotary spindle journaled in said carriage and carrying a shell-holder, means for feeding the carriage toward the 50 dies, a rotary fluid motor, gearing for transmitting rotary motion from said motor to said spindle, a fluid supply pipe for said motor having a manual controlling valve, and manual controlling means for said carriage-feed mechanism, said valve and said controlling means being arranged in proximity to each other at the same side of the machine.

4. In a machine of the character described, 60 the combination of a pair of coöperating dies, a carriage movable toward and from said dies, a rotary spindle journaled in said carriage and carrying a shell-holder, means for feeding the carriage toward the 65 dies, a rotary motor mounted on said carriage above said spindle and having its driving shaft arranged lengthwise thereof, gearing connecting said shaft with said spindle, and means for controlling said 70 motor.

5. In a machine of the character described, 75 the combination of a power hammer including its stationary and movable dies, a horizontal carriage movable toward and from said dies, a rotary spindle journaled lengthwise in said carriage and provided at its front end with a shell-holder and at its rear end with a gear wheel, a rotary fluid-pressure motor arranged above 80 said spindle and mounted on said carriage, the driving shaft of said motor having a pinion which meshes with the gear wheel of said spindle, a pressure supply-pipe leading to said motor and having a controlling valve, 85 and means for feeding said carriage toward said dies, said means including a hand-wheel arranged at one side of the machine, said controlling valve being arranged at the same side of the machine as said hand wheel and 90 in proximity thereto to be operated by one and the same operator.

RODERICK J. WHELAN.
